CLAIM

The ornamental design for an adjustable lathe work stop, as shown and described.

DESCRIPTION

FIG. 1 is a perspective view of an adjustable lathe workstop showing my new design with the components axially spaced apart;

FIG. 2 is a right side elevational view with the components in touching relationship;

FIG. 3 is a top plan view of FIG. 2;

FIG. 4 is a rear elevational view of FIG. 2;

FIG. 5 is a front elevational view of FIG. 2;

FIG. 6 is a left side elevational view of FIG. 2;

FIG. 7 is a bottom plan view of FIG. 2.
